UNITED STATES PATENT OFFICE

JULIUS DORNETH, OF KONRADSHOHE, NEAR TEGEL-BERLIN, GERMANY, ASSIGNOR TO
TYPOGRAPH G. M. B. H., OF BERLIN, GERMANY

RING SPACER FOR MATRIX SETTING AND TYPE LINE CASTING MACHINES

Application filed December 8, 1931, Serial No. 579,781, and in Germany May 22, 1931.

This invention relates to improvements in ring spacers for matrix setting and type line casting machines in which the spacers, like the matrices, are suspended on a wire and guided in a circular path, and in which the lines set are conveyed by a slide to the casting point into a vertically adjustable carriage and after casting are conveyed by the said carriage upwards to the distributing point. 5
10 The invention is applicable both to single and to double ring spacers, and will be described in the following in connection with double spacers, which are more advantageous for long matrix bars, having two single 15 spacers of circular shape arranged one above the other.

The non-rotatable parts of such double-ring spacers are connected together in a well-known manner by means of a bridge, at one 20 side of which are situated the rotatable wedge rings. The bridge is provided at the top with an arm, the upper end of which has a hook by means of which the spacers, like the matrices, are suspended on a guide wire. The ring 25 spacers are provided in the usual manner in their axis with square openings by means of which they rest during the justifying operation on square spindles, by turning which the justifying of the line is effected. The use of 30 such ring spacers, which as is well known ensure good justifying, has only been possible in machines of the kind above referred to since it has been shown according to German Patent No. 485,370, that the square spindles 35 provided for the turning of the wedge rings may be arranged in such an adjustable manner that after the casting, they can be withdrawn from the ring spacers in order that it should be possible then to convey the spacers 40 having with the matrices in the carriage, upwards to the distributing point. In the machines built in accordance with this principle, the ring spacers during their circulation do not move with their axial square openings 45 or recesses on corresponding rods, but their circulation is brought about as already mentioned in the same way as that of the matrices, by guiding them by means of extension arms provided on their non-rotatable 50 parts, and of hooks arranged thereon, on a

guide wire. Like the matrices, they are released by striking a key and slide down along their guide wire to the collecting or setting point.

After setting of the lines is finished, they 55 are carried by a slide into the carriage to the casting point. In this position they are to justify the lines, and to that end they are suitably turned by square spindles passing through their axial openings. 60

The arrangements on machines provided with such a circuit are such that the square spindles are brought in front of the casting point and that during the transfer of the line set from the setting (collecting) point 65 to the casting point, all the ring spacers of this line arrive with their axial square openings on the square spindles.

After casting, the square spindles are turned back again to their original positions 70 and are withdrawn from the ring spacers, so that the latter can be conveyed by the carriage upwards to the distributing point in order to complete their circuit.

In the ring spacers used hitherto, the 75 wedge rings, owing to their irregular weight distribution, have a tendency as soon as the square spindles are withdrawn from the openings to turn in such a manner that the thickest parts thereof hang downwards; the 80 rings being assisted in this tendency by the vibrations of the machine. The square openings of the wedge rings assume therefore oblique positions different from one another, so that smooth pushing of the ring spacers over the square spindles is impossible. 85 Jamming and bending occur which always results in trouble in working, for on that account the lines set frequently cannot be 90 pushed over to the casting point.

The object of the present invention is to 95 eliminate this drawback of the ring spacers hitherto used and to ensure by a special arrangement on the ring spacers that the wedge rings brought back to their initial position after casting, shall be held immovably also during the distributing and setting operation, in this initial position which is the same for all, in order that all the square openings 100

should be always in the position required to receive the square spindles.

- This object is attained by securing to each rotatable wedge ring a spring blade which in the initial position engages over the non-rotatable part (bridge) of the ring spacer in such a manner that the said bridge is firmly clamped between the wedge ring and the spring. The pressure of the springs is calculated in such a manner as to prevent the wedge rings from moving out of their initial position under the action of their irregular distribution of weight and of any vibration of the machine.
- 15 A construction according to this invention is illustrated by way of example in the accompanying drawings showing a double ring spacer.

Figure 1 shows in plan such a double spacer, full size.

Figure 2 is a cross-section on line II—II of Figure 1, on an enlarged scale.

Figures 3 to 6 show perspective details of the arrangement.

- 25 The double spacer comprises a non-rotatable or stationary part 1 which, as is well known, is made similar to the matrix bar and suspended with its hook-shaped upper end on a guide wire, and which has in the usual manner two annular portions 1' defining circular openings in which the wedge rings 2 turn with their hubs 3. In the center of the wedge rings 2 are provided the axial square openings 4, the dimensions of which correspond to those of the square spindles. In order to prevent the wedge rings 2 from dropping out of the openings of the annular portions 1' of the non-rotatable part 1, on the hubs of the wedge rings are provided 35 disc-shaped collars 5, the diameters of which are greater than the corresponding openings of the non-rotatable part 1. At the thickest points of the wedge rings 2 are secured 40 spring blades 6 in such a manner that in the initial position they press against the part 1 and clamp it between themselves and the wedge rings. These springs 6 could of course also be made in one piece with the disc-shaped collars 5 since these discs are also 45 secured to the wedge rings. In order to secure the wedge rings in their initial position in a particularly reliable manner, a still stronger hold can be given to the springs 6 in the said position by providing the non-rotatable part 1 of the spacer with corresponding 50 grooves 7 with which the springs 6 engage in the initial position of the wedge rings.

55 After casting the line, the square spindles automatically turn back to their initial position and bring thereby all the wedge rings 2 of a set line also to their initial position which is the same for all of them. In this position however the springs 6 reach the 60 grooves 7 and hold the wedge rings 2 fast in this initial position. The square spindles

can be now withdrawn from the ring spacers, and the latter carried with the matrices upwards to the distributing point whence they glide down along the guide wire to their cases in order thus to begin again their circulation without the wedge rings 2 turning out of their initial positions. This ensures that the square openings 4 of all the wedge rings 2 shall always have the correct position required for a smooth transfer of the 75 ring spacers to the square spindles.

Having now fully described the invention what is claimed as new and desired to be secured by Letters Patent is:—

1. A ring spacer for matrix setting and type line casting machines, comprising a non-rotatable part including an arm, an annular portion carried thereby, a hook on the upper end of the arm for suspending the arm from a guide wire, a rotatable wedge ring on the annular portion, a spring secured to the rotatable wedge ring, and in the position of rest of the wedge ring, engageable over the non-rotatable part of the spacer for clamping the same between itself and the wedge ring so that the latter is held fast in its initial position during the circulation of the spacer on the guide wire.

2. A ring spacer according to claim 1, wherein a disc-shaped collar is secured to the wedge ring and wherein the spring is in the form of a tongue forming part of the disc-shaped collar.

3. A ring spacer according to claim 1, characterized in that for the purpose of increasing the hold of the spring, the non-rotatable part of the spacer is provided with a groove into which the spring snaps in the initial position of the wedge ring.

4. A ring spacer as claimed in claim 1, wherein an additional annular portion is provided, a bridge joining said additional annular portion of the arm, a rotatable wedge ring on the additional annular portion, and a retaining spring on the ring.

In testimony whereof I affix my signature.

JULIUS DORNETH.
